MATERIAL HANDLING MECHANISM

Nils D. Levin, Columbus, Ohio, assignor to The Jeffrey Manufacturing Company, a corporation of Ohio

Original application April 30, 1930, Serial No. 448,626. Divided and this application January 21, 1935, Serial No. 2,624

8 Claims. (Cl. 198—8)

My invention relates to track-mounted loading machines particularly of the type adapted for use in coal mines, and one of the objects of the invention is the provision of means for retaining above the mine track the receiving portion of conveying apparatus while the gathering mechanism is operated in advance of the mine track.

Another object of the invention is to combine with the forward receiving end of a conveyor, means for engaging the mine track to prevent lateral movement of such receiving end while gathering mechanism is operating arcuately in advance of the mine track while delivering material to such receiving end.

More particularly it is the object of the present invention to provide a pair of flanged wheels for the forward receiving end of a conveyor of a loading machine to prevent lateral movement of such receiving end relatively to the mine track while such flanged wheels engage the latter during swinging movements of the gathering conveyor operating to deliver material to such receiving end.

Another object of the invention is the provision in a track mounted loading machine having a gathering conveyor connected to the forward receiving end of a swinging receiving conveyor, of wheels for such receiving end for transportation purposes along a mine track and also for preventing lateral movement of the said receiving end when the gathering conveyor is operated arcuately over the mine floor in advance of the mine track.

Other objects of the invention will appear hereinafter, the novel features and combinations being set forth in the appended claims.

In the drawings:

Fig. 1 is a side elevational view of the rear end of a machine embodying my invention showing the discharge conveyor section;

Fig. 2 is a side elevational view of the front end of the machine of Fig. 1, showing the gathering conveyor section;

Fig. 3 is a somewhat diagrammatic plan view of the device of Figs. 1 and 2 illustrated as performing a material gathering operation;

Fig. 4 is a view similar to Fig. 3 in which the gathering conveyor is completing a gathering operation by swinging about its vertical axis of movement; and

Fig. 5 is a side elevation of the machine associated with a pony truck for transportation along mine tracks.

This application is a division of my application for Material handling mechanism, Serial No.

448,626, filed April 30, 1930, which issued as Patent No. 1,997,589 on April 16, 1935, and is a continuation in part of my application for Material handling mechanism, Serial No. 480,216, filed September 6, 1930, which issued as Patent No. 1,997,591 on April 16, 1935.

As has been mentioned, the present machine comprises generally a discharge or receiving conveyor, and a gathering conveyor which have been indicated on the drawings as A and B, respectively. The discharge conveyor A is the same (with some additions, as will hereinafter appear) as the pit car loader described and claimed in my Patent No. 1,997,588 dated April 16, 1935. Only a brief description of this conveyor unit will thus be necessary.

Referring particularly to Fig. 1, a truck frame 20 is provided with wheels as at 21 and 22 adapted to engage a mine track, of which one of the rails is shown at 23. Mounted on frame 20 is a frame or turntable 24 for pivotal movement about a vertical pivot as shown in full detail in each of the aforementioned Patents Nos. 1,997,589 and 1,997,591. A shaft 26 is journaled in bearings of frame 24, and pivotal about this shaft is a conveyor trough 27. The delivery end 27' of the conveyor trough is pivoted to the forward end about a shaft 28, and rests on a bolster 29 which is vertically adjustable on threaded rods 30 depending from the ends of brackets 31 fixed to the extremity of the forward portion of trough 27.

An electric motor 32 mounted on frame 24 drives a countershaft 33 through a sprocket chain 34. An idler sprocket 35 engages the chain to hold it clear of a winding drum 63 and its control appurtenances.

As disclosed more in detail in my above mentioned applications, the countershaft 33 is connected to shaft 26 through chain and sprocket means, and through the intermediary of a manually controllable clutch, which shaft 26 carries sprockets for driving draft chains movable in the conveyor trough 27 of discharge conveyor A, between which chains extend material conveying flights. In addition, there is provided appropriate chain and sprocket means directly connecting the countershaft 33 to the shaft 45 whereby said shaft 45 is always rotating when countershaft 33 is rotated. An appropriate clutch is provided to connect a continuous universally flexible drive chain 52 to the shaft 45 and to the wheels 21 and 22 of the truck, which chain 52 extends over guide sheaves 53 and 54 and around sheaves 55 and 56 fixed to the shafts of said wheels 21 and 22. Thus, the conveyor unit com-

prises a self-contained unit which may be moved about a mine under its own power.

Loosely journaled on shaft 45 is a drum 63 adapted to receive a rope or cable 169, the functions of which are hereinafter described. Said drum is connected to shaft 45 through a releasable friction clutch operable from lever 79. In addition, said drum carries a braking flange or pulley with which cooperates a manually operable 10 brake mechanism including a lever 80 which may be held in an adjustable position by a well-known pawl-ratchet means 86.

In addition to the pivotal relation provided between the forward and rear sections of the conveyor A about pivot 28, the whole conveyor is 15 pivotal about the shaft 26 relative to the truck 20. Pivotal movement of said conveyor on said truck 20 about a vertical axis is also provided, as above mentioned.

20 Trough 27 at its forward end extends downward in proximity to the track rails and has a forward receiving portion 27" adapted to assume a substantially horizontal position immediately above the rails. At substantially the end of the 25 downwardly extending portion of the trough 27, there is erected an upright frame generally denoted at 89, this frame being composed of structural steel parts. Attached to the frame 89 for pivotal movement about a vertical axis on a 30 mounting 90, is a crane jib 112 having at its forward end a pair of sheaves 114 about which are reeved sections of the rope or cable 169 for lifting the gathering conveyor B about its vertical pivot 165.

35 On a laterally projecting horizontal plate 120 secured forwardly of drum 63 and on the same side of the machine as the latter, are mounted on vertical axes two sheaves 121 and 122, Figs. 1, 3 and 4. On the other side of the trough and carried on a plate 124 secured to the trough is a sheave 123 mounted on a vertical axis, Figs. 3 and 4.

The principal feature of the present invention 45 is the combination of the flanged rollers 131 for supporting the receiving end or trough section 27" of the conveyor A which is pivoted to the truck 24 to swing on a vertical axis. The flanged rollers 131 are pivoted at 132 to brackets 129 secured to the lower ends of the opposite uprights of the 50 frame 89. Two of such rollers 131 are mounted on the frame 89 each roller having its flange extending along the outer edges of the heads of the rails, or each roller 131 may be provided with parallel spaced-apart flanges to embrace the 55 opposite edges of the heads of the rail on which the roller rests. As is hereinafter more fully set forth, the rollers 131 are adapted not only to support the forward portion or the receiving end 27" of the conveyor A during such loading operation as 60 that illustrated in Fig. 3, but the flanges of the rollers 131 by engaging the lateral edges of the rails 23 also prevent lateral movement of the receiving end 27" of the conveyor A when the gathering conveyor B is operated by pivotal swinging thereof as illustrated in Fig. 4.

At the forward end of trough section 27" and on the underside thereof is secured a vertical pivot member 133, Fig. 2, which is engaged by one end of an arm 134 having an expanded vertical web 70 portion 135 adapted to swing about the forward end of the trough. Just above the top of the trough, web 135 has secured thereto a horizontal angle bar 136 on the lower side of the horizontal web of which is mounted a centrally disposed lug 75 137. To the outer end of the conveyor trough 27"

and at its top is secured a circular casting 138 having a peripheral upstanding rib 139 which forms a guide for lug 137. Casting 138 and rib 139 are adapted to support any weight imposed thereon through bar 136.

5 The gathering conveyor B, Fig. 1, comprises a bottom plate 140 bent upward at one end so as to be adapted to project above the receiving end of the discharge conveyor A, with its forward portion in substantially horizontal position. Extending longitudinally of plate 140 and secured thereto substantially centrally thereof are upper and lower chain guides 141 and 142 spaced apart by means of blocks. Guides 141 and 142 are provided on opposite sides with longitudinal grooves, 15 in which are engaged elements of a chain 146 which is flexible in planes both parallel and perpendicular to plate 140. At intervals, flights 147 are secured to chain 146 to project laterally of plate 140 so as to propel material therealong and 20 on one side or the other of the chain guiding means, depending upon the direction of travel of the chain. A plate 148 is secured to the tops of the upper chain guide members 141, and extending longitudinally and centrally of plate 148 25 is an upright baffle plate 149. At its forward end, plate 149 terminates at an upright post 150 having an upper bifurcated end, Fig. 2. At its rearward end, the plate 149 terminates in a block 151 in which are mounted on a horizontal transverse 30 axis a pair of sheaves 152.

In a casting at the rear end of the gathering conveyor B and mounted upon the chain guides, is journaled a shaft 154 in perpendicular relation to base plate 140. On the lower end of shaft 154 35 is fixed a sprocket which engages chain 146 to drive the latter. To the upper end of shaft 154 is keyed a bevel gear 156 engaged by a bevel pinion keyed to the end of a shaft 158 journaled in a bearing 159. A reversible motor 160 is 40 mounted on the tops of the chain guides with its armature shaft in alignment with shaft 158 and in driving connection therewith through a coupling 161.

The inclined portion of conveyor B is provided 45 with upwardly extending side plates 163 to hold the coal on plate 140 as it travels up the incline, the rearward end of plate 140 being cut away, as indicated at 162, to permit the coal to drop readily into the receiving end of the discharge conveyor.

A casting 164 secured to the underside of plate 140 at its rearward end has integral therewith a pair of trunnions of which one is shown at 165, these resting on the angle member 136 and being 55 engaged by retaining angles as at 166. It will be noted that the trunnions are so journaled as to give them a considerable freedom of movement in an upward direction relative to the mounting member constituted by elements 134, 135 and 136. 60

The jib 112 is pivoted on a vertical axis on the upper forward end of frame 89 and is adapted to extend above the gathering conveyor. The rope 169 having one of its ends engageable with drum 63 may have its other end portion reeved about 65 suitable pulleys and led from the end of the jib 112 downward to pulleys 152 on the gathering conveyor. By suitable manipulation of the drum 63, the gathering conveyor may be elevated, as for disposition on a pony truck for transportation. 70 This arrangement is fully described in my above mentioned Patent No. 1,997,591. Due to the pivoting of the boom and the gathering conveyor, the latter may be swung about its pivot 133 in elevated position, the placing of the last named 75

pivot being such relative to the delivery end of the gathering conveyor, as to maintain the latter always in proper delivering position relative to the receiving end of the discharge conveyor.

Upon operating drum 63 to tension rope 169, the gathering conveyor may be swung upwardly about its supporting trunnions 165 and in its raised or lowered position may be swung about vertical pivot 133, the placing of the pivot being such relative to the delivery end of the gathering conveyor as to maintain the latter always in proper delivering position relative to the receiving end of the discharge conveyor.

For transporting the machine along the mine track from place to place in the mine, reliance may be had on the flanged wheels 131 while the hoisting rope 169 is in place on the machine as shown in Figs. 1 and 2 and wound up on the rope drum 63 sufficiently to elevate the gathering conveyor B to clear the mine track. If a pony truck 190 (Fig. 5) is available with a supporting bolster 183' pivoted to and projecting upwardly from its central portion, the cup-like member 183 may be positioned to bear on such bolster 183' to support the gathering conveyor and the receiving end 27" of the conveyor A, during transportation as shown in Fig. 5. The cup 183 is located to the left of the center of gravity of the gathering conveyor B, as viewed in Fig. 2, and therefore when the gathering conveyor B rests on the bolster 183' of the pony truck 190, the rope drum 63 may be released sufficiently to permit the rope 169 to lower the outer and forward end of the gathering conveyor B, thereby lifting by means of the connections shown at 165 and 166 in Fig. 2, the forward receiving end 27" of the conveyor A together with the flanged wheels 131, up off the mine track. Consequently, when the pony truck 190 is used for supporting the gathering conveyor B and the forward receiving portion of the conveyor A, as shown in Fig. 5, the swivelling of the conveyor A on its vertical axis relative to the truck 24 and the swivelling of the gathering conveyor B relative to the pony truck, will enable

the loading machine to travel along curved portions of a mine track in narrow entries of the mine. When the pony truck is not available the hoisting mechanism may maintain the gathering conveyor in sufficiently elevated position to clear the mine track, and the loading machine may travel along curved portions of a mine track in narrow entries if care be taken to swing the gathering conveyor on the pivot 133 so that it will not strike against the walls of the narrow entry. Along straight portions of the mine track the wheeled truck and the flanged wheels 131 will be sufficient to maintain the conveyor A above the mine track with little or no tendency for the gathering conveyor to swing out of alignment or from its adjusted position above the mine track.

In Figs. 3 and 4, there are illustrated two positions of the device when operating to perform its function, according to one method of operation thereof. As here illustrated in Fig. 3, the discharge conveyor A is disposed on a straight track section and supported by means of its truck mounting, and also by means of rollers 131. The gathering conveyor B rests on the mine floor in advance of the track, and is being sumped into a mass of material through a rope 184 secured at its forward end to a roof-jack 185 and its rearward end engaged with drum 63 for winding thereon. The intermediate portion of the rope is guided clear of the machine by sheave 122. When the horizontal portion of conveyor B has

been sumped into the material, a jack 186 is placed to the left of the machine, rope 184 is reeved around sheaves 121 and 123 as shown in Fig. 4, around a pulley 187 having its block 188 anchored to jack 186, and its forward end caught in the upper slotted end of post 150, an eye 189 fixed to the end of the rope preventing the latter from pulling away from the post. Upon exerting tension on the rope through manipulation of the winding drum, conveyor B may be swung to the left to engage its gathering end laterally in the material. Upon the completion of this operation, jack 186 may be moved to the right of the machine and rope 184 trained around sheave 122 and pulley 187 to swing conveyor B to the right, the direction of rotation of motor 160 being reversed.

Rope 184 being secured to conveyor B at the top of post 150 has a tendency to tilt the conveyor about its longitudinal axis, this tendency being accommodated readily by the bearings for trunnions 165. This tilting of the gathering conveyor gives it a superior scraping action, and allows it to engage itself readily under the material and leave a clean floor.

It should be particularly noted that the endless driving chain 52 is sufficiently flexible and sufficiently slack to permit the turntable 24 to move through an angle of about 45° on each side of the mine track. It is desirable to run the flanged wheels 131 off the ends of the mine track and swing the conveying apparatus A, B on the vertical axis of the turntable 24 relatively to the truck frame 20 so as to secure a greater reach for the gathering conveyor B during operation for loading coal at the working face in very wide entries or rooms. When the conveyor apparatus is thus adjusted at an angle to the mine track, the flanged wheels 131 may rest on the mine bottom and be relied on to assist in preventing the receiving portion 27" from skidding sidewise when the gathering conveyor B is swung on its pivotal connection 133 relative to the discharge conveyor A. However, the anchoring jack 186 may be set in such a position that the pull on the rope 184 between the pulley 187 and the post 150 will be nearly at right angles to the gathering conveyor B, whereas that portion of the rope 184 between the pulley 123 and the pulley 187 will be nearly parallel to the discharge conveyor A. There will then be little tendency to swing the receiving portion 27" sidewise while at the same time considerable force will be exerted in swinging the gathering conveyor on its pivot 133.

It should also be noted that the rope 184 when arranged as shown in Fig. 4, extends transversely of the discharge conveyor A between the flanged wheels 131 and the truck. The pull on that portion of the rope 184 between the pulley 123 and the pulley 187 will be resisted partly by the truck and partly by the flanged wheels 131. In other words, while the discharge conveyor A is mounted on the truck and also on the flanged wheels 131, the pull rope is extended from the supporting framework at a point intermediate the flanged wheels 131 and the truck, thereby taking advantage of the flanged wheels of the truck as well as the flanged wheels 131 for securing a firm anchorage for the discharge conveyor A while the gathering conveyor B is being swung along an arc on its pivot 133 relatively to the discharge conveyor A, as illustrated in Fig. 4.

It is evident that when a gathering operation is performed, as illustrated in Fig. 4, there will be a tendency for the forward portion 27" of the

trough 27 of discharge conveyor A to be moved laterally of the rails. To prevent such movement and thereby to maintain the discharge conveyor A in proper position, as well as to support the forward portion thereof, is the particular function of wheels 131.

In the operation of the device, the coal is, of course, first gathered by the gathering conveyor B and discharged into the forward portion 27' of trough 27 of discharge conveyor A. Conveyor A then transports the coal to its discharge end 27 where it is discharged into cars on the mine tracks or onto any other desired device.

Obviously those skilled in the art may make various changes in the details and arrangement of parts without departing from the spirit and scope of the invention as defined by the claims hereto appended, and I wish therefore not to be restricted to the precise construction herein disclosed.

Having thus described and shown an embodiment of my invention, what I desire to secure by Letters Patent of the United States is:

1. In a loading machine, the combination with a truck adapted to travel on a mine track, of a receiving conveyor mounted thereon for adjustment relative thereto on an upright axis and extending beyond said truck with the front end in a lowered position, additional track engaging supporting means for the front portion of said receiving conveyor adapted to prevent lateral movement thereof, a gathering conveyor pivoted to the forward end of said receiving conveyor and adapted to swing relatively thereto on an upright axis while in delivering communication with said receiving conveyor, and rope gearing for swinging said gathering conveyor and comprising means for directing the pulling rope laterally from the receiving conveyor intermediate said truck and said supporting means to the front portion of said gathering conveyor.

2. In loading apparatus, the combination with a truck, of a receiving conveyor mounted thereon for adjustment relative thereto on an upright axis and extending forwardly and downwardly from said truck, additional means on the forward portion of said receiving conveyor for supporting said forward portion near the mine bottom, a gathering conveyor pivoted to the forward end of said receiving conveyor to swing relatively thereto on an upright axis, rope winding mechanism, a rope extending from said winding mechanism to the front end portion of said gathering conveyor, a pulley connected to an anchorage extraneous to the machine for predetermining the direction of pull on the outer end portion of said gathering conveyor, and means for guiding the rope laterally to said pulley from under said receiving conveyor at a position intermediate said truck and said additional supporting means.

3. In a loading machine, the combination with a truck movable along a trackway, of a receiving conveyor pivotally mounted thereon and extending downwardly and forwardly into proximity to said trackway, abutment mechanism carried by said conveyor between said forwardly extending portion of said conveyor and said trackway and in association with the latter, a gathering conveyor connected to said receiving conveyor to swing relatively thereto on an upright axis in advance of said trackway, and means comprising rope gearing connected between said conveyors and cooperating with said abutment mechanism to swing the gathering conveyor as aforesaid to gather material for delivery to said receiving conveyor while said abutment mechanism prevents pivotal movement of said receiving conveyor relative to the truck.

4. In loading apparatus, the combination with a truck adapted to travel on a mine track, of a conveyor having a receiving end adjacent to the mine track and mounted on said truck for adjustment relatively thereto on an upright axis, a gathering conveyor pivotally connected to said receiving end for swinging movement relatively thereto on an upright axis, means comprising a pair of flanged rollers connected to said receiving end in position to engage the rails of the mine track and support such receiving end thereon while at the same time bracing such receiving end against lateral movement due to swinging of the gathering conveyor, and means for swinging the gathering conveyor for gathering operation on its upright axis relatively to said receiving conveyor while lateral movement of the front end of said receiving conveyor is resisted by the flanged rollers engaging the rails of the mine track as aforesaid.

5. In loading apparatus, the combination with a truck adapted to travel on a mine track, of a conveyor mounted on said truck for adjustment relative thereto on an upright axis, the front end of said conveyor being adapted to occupy a position adjacent to the mine track, a gathering conveyor pivotally connected to said relatively low front end of said first-named conveyor for swinging movement relatively thereto on an upright axis, means carried by the relatively low portion of said first-named conveyor in position to engage the sides of the mine track while the front end of said first-named conveyor is supported thereon, and means for operating said gathering conveyor to gather a load by swinging the same on its upright axis relatively to said first-named conveyor while in delivery communication with the latter and while said delivery conveyor is prevented by said track engaging means from moving laterally relatively to said truck.

6. In loading apparatus, the combination with a truck adapted to travel along a mine track, of a receiving conveyor mounted on said truck for lateral adjustment relative thereto on an upright axis, means on the forward portion of said receiving conveyor for confining the latter against lateral movement relatively to the mine track but permitting longitudinal movement of the receiving conveyor along the mine track, a gathering conveyor pivotally connected to the forward end of said receiving conveyor for swinging movement relatively thereto on an upright axis, a rope winding mechanism mounted on said truck, a rope connected to said rope winding mechanism and having its free end adapted to be connected to an anchorage in the mine extraneous to the machine, truck propelling mechanism for moving the truck together with said receiving conveyor along the mine track while said gathering conveyor engages the ground surface in advance of the mine track to effect sumping of the gathering conveyor into a pile of material to be loaded, and means for guiding the rope from the rope winding mechanism to an anchorage on the gathering conveyor, the construction and arrangement being such that when the winding mechanism is operated while the rope is thus guided to the gathering conveyor the latter will be swung on its upright pivotal axis relatively to the receiving conveyor while the latter is confined

against lateral movement relatively to the mine track as aforesaid.

7. In a loading machine, the combination with a truck adapted to travel on a mine track, of a receiving conveyor mounted on said truck for adjustment relative thereto on an upright axis, means for supporting the front end of said receiving conveyor on the mine track while preventing lateral movement of said receiving conveyor relatively to the mine track, a gathering conveyor pivotally connected to the forward end of said receiving conveyor for swinging movement relatively thereto on an upright axis while remaining in delivery communication with said receiving conveyor, and rope gearing comprising a rope extending from rope winding mechanism along guiding means transversely of the receiving conveyor in advance of the truck to and around a guiding pulley connected to an anchorage in the mine extraneous to the machine and thence to the front end portion of said gathering conveyor, the construction and arrangement being such that the supporting means for the front end of the receiving conveyor resists the tendency of the rope extending transversely of the receiving conveyor in advance of the truck to swing the receiving conveyor on its upright axis relatively to the truck.
8. In a loading machine, the combination with a truck adapted to travel on a mine track, of a receiving conveyor mounted thereon for adjustment relative thereto on an upright axis, flanged

wheels on the forward portion of the receiving conveyor in position to co-operate with the truck to support the said conveyor for transportation on the mine track, a gathering conveyor pivotally connected to the forward end of said receiving conveyor for swinging movement relatively thereto about both horizontal and upright axes, rope winding mechanism, rope means connected to said rope winding mechanism, means for enabling said rope means when operated by said rope winding mechanism to swing said gathering conveyor on its horizontal axis into position to clear the mine track for transportation while the machine is supported by said truck and said flanged wheels, and means for enabling the rope means when operated by said rope winding mechanism to swing the gathering conveyor on its upright axis when said gathering conveyor is in ground engaging gathering position in advance of the mine track, the construction and arrangement being such that when the gathering conveyor is held by said rope means clear of the mine track the machine is supported for transportation by said truck and said flanged wheels and when said rope means is operated to perform a gathering operation said flanged wheels not only support the front end of the receiving conveyor but also resist the tendency of the gathering operation to swing the receiving conveyor on its upright axis relatively to said truck.

NILS D. LEVIN.
